US0D1082627S

(12) **United States Design Patent** (10) Patent No.: **US D1,082,627 S**
(45) Date of Patent: ** Jul. 8, 2025

(54) **AUTOMOTIVE VEHICLE FRUNK LID**

(71) Applicant: **Atieva, Inc.**, Newark, CA (US)

(72) Inventors: **Derek N. Jenkins**, Malibu, CA (US);
Grimaud Gervex, San Francisco, CA (US); **Jiyeon Kim**, San Francisco, CA (US); **Simon Tovey**, Fremont, CA (US)

(73) Assignee: **Atieva, Inc.**, Newark, CA (US)

(***) Term: **15 Years**

(21) Appl. No.: **29/859,786**

(22) Filed: **Nov. 14, 2022**

(51) LOC (15) Cl. **12-08**

(52) U.S. Cl.

USPC **D12/173**

(57) **CLAIM**

The ornamental design for an automotive vehicle trunk lid, as shown and described.

DESCRIPTION

FIG. 1 is a perspective view of an automotive vehicle trunk lid, of the new design;

FIG. 2 is an enlarged perspective view thereof;

FIG. 3 is a top view thereof;

FIG. 4 is a front view thereof;

FIG. 5 is a side view thereof;

FIG. 6 is a side view thereof, opposite that of FIG. 5;

FIG. 7 is a bottom view thereof; and,

FIG. 8 is a back view thereof.

The broken and dotted lines of FIGS. 7 and 8 indicate portions therein which form no part of the claimed design. The broken and dashed lines (e.g., the "LUCID" text and front circle) are for environmental illustrative purposes only and form no part of the claimed design.

1 Claim, 7 Drawing Sheets
